Wm. H. Page

United States Patent Office.

WILLIAM H. PAGE, OF NORWICH, CONNECTICUT, ASSIGNOR TO WM. H. PAGE & CO., OF SAME PLACE.

Design No. 4,285, dated August 9, 1870.

DESIGN FOR TYPE-BORDER.

The Schedule referred to in these Letters Patent and making part of the same.

I, WILLIAM H. PAGE, of Norwich, in the county of New London, State of Connecticut, have invented or produced a new and original Design for a Border for printing purposes, styled "Chain-Border."

My design is for a border, as shown and described by the accompanying impression, which may be printed in one or more colors.

I claim as my invention—
The design for a border, as shown.

WM. H. PAGE.

Witnesses:

JAMES D. MOWRY,
CHARLES C. FULLER.
